UNITED STATES PATENT OFFICE.

CHARLES F. COLE AND QUINCY CARR, OF HUNTINGTON, WEST VIRGINIA.

GAS-BURNER.

1,185,771.

Specification of Letters Patent.

Patented June 6, 1916.

Application filed August 30, 1915. Serial No. 48,062.

To all whom it may concern:

Be it known that we, CHARLES F. COLE and QUINCY CARR, citizens of the United States, residing at Huntington, in the county of Cabell and State of West Virginia, have invented certain new and useful Improvements in Gas-Burners, of which the following is a specification, reference being had to the accompanying drawings.

10 This invention relates to improvements in gas burners, and has for its primary object to provide an improved burner construction which is applicable to various types of gas stoves or grates, and will produce a maximum of heat from a minimum consumption of fuel.

Another object of the invention is to provide a burner for the above purpose having independent flues or passages, each provided 20 with jet orifices or outlets, and improved means for independently controlling and regulating the supply of gas to said flues or passages.

Our invention has for another very important object to provide a gas burner of the above character and improved means for mounting and utilizing an air mixer in connection therewith.

It is still another object of our invention 30 to provide an improved mixer construction having a plurality of gas receiving chambers, the gas from the respective flues of the burner being alternately discharged into the several chambers of the mixer.

35 The invention has for an additional object to generally improve the construction of gas burners of the above character whereby the efficiency, durability, and serviceability of such burners is materially enhanced.

40 With the above and other objects in view, our invention consists in the novel features of construction, combination, and arrangement of parts to be hereinafter more fully described, claimed, and illustrated in the accompanying drawings, in which,

Figure 1 is a front elevation of a portable heating stove, a portion of the same being broken away to show our improved burner mounted therein; Fig. 2 is a plan view, partly in section, of the burner body; Fig. 3 is an enlarged vertical section taken on the line 3—3 of Fig. 1; Fig. 4 is a transverse section taken on the line 4—4 of Fig. 1; Fig. 5 is a section taken on the line 5—5 of Fig. 3; Fig. 6 is a detail elevation of the gas cock or valve for admitting the gas to the cham-

bers of the supply head; Fig. 7 is a vertical section similar to Fig. 4 showing a modified construction and mounting of the mixer; Fig. 8 is a section taken on the line 8—8 of Fig. 7; Fig. 9 is a detail perspective view of one of the metal plates from which the mixer is formed, illustrating a slightly different construction of the same from that shown in Fig. 8; Fig. 10 is a transverse section illustrating another form of the mixer; Fig. 11 is a longitudinal section taken on the line 11—11 of Fig. 7; and Fig. 12 is a detail section of the construction shown in Fig. 9.

Referring in detail to the drawings and more particularly to Figs. 1 to 6 thereof, 5 designates a portable heating stove which may be of any ordinary or approved construction, the same including a curved reflecting back plate indicated at 6, or an asbestos wall which is frequently employed instead of such a reflecting plate. While we have illustrated our invention employed in connection with such a portable heating stove, it is, nevertheless, to be borne in mind, 70 that the same is not limited to such specific application and use, but may also be utilized as the flame producing adjunct of various types of heating or cooking stoves now known in the art.

Within the open front of the stove and at either the top or bottom thereof, as the case may be, our improved burner generally indicated at 7, is horizontally arranged.

The body of this burner is made up of a plurality of sections, as clearly illustrated in Fig. 4. These body sections include an outer sheet metal plate 8 which is of channel form in cross-section and is provided upon its longitudinal edges with the outwardly projecting flanges 9. This channel shaped plate forms the front and rear walls 10 and 11, respectively, and the top wall 12 of the burner body. The top wall 12 is provided at spaced points with a plurality of jet orifices in which the burner tips indicated at 13 of any suitable type, are conveniently secured.

It will be understood that if desired, the wall 12 may be punched outwardly at intervals to form the tips, the apexes of which are perforated to provide jet openings. A second longitudinally extending channel shaped sheet metal plate 14 is arranged within the outer body plate 8. The body wall 15 of this plate 14 extends between the front wall of the body plate 8, and a base or bottom wall 16. The longi-

tudinal edges of the channel plate 14 are also flanged outwardly as at 17. The longitudinal edges of the bottom wall 16 are bent over and clenched upon the flanges 9 and 5 17 of the channel plates, as indicated at 18. Thus the several parts of the burner body 70 may be securely held against relative movement in their assembled position.

The top wall 12 of the burner section 8 is 10 formed with spaced openings 19 which are alternately arranged with respect to the burner tips 13. It will, however, be understood that if desired, the openings and 15 burner tips in the wall 12 may be arranged in multiples of two or more. Through the 20 openings 19, the burner tubes 20 which are integrally formed upon the wall 15 of the body member 14, extend, said latter tubes projecting from the face of the wall 12 to substantially the same extent as the tips 13. The tubes 20 are provided with suitable jet tips.

It will be seen, from the above description, that the burner is thus provided with 25 non-communicating longitudinally extending flues or passages, and these flues are closed at one of their ends by the plates indicated at 21 which are set in the ends of the 30 flues and brazed or otherwise permanently secured to the walls thereof. Each of these 35 end plates is provided with a central interiorly threaded boss 22.

23 designates the supply head which, when connected to the burner body, extends at 40 right angles to the plane of said body. This supply head is provided at one end with an interior central longitudinally extending partition wall 24 which divides the same into separate compartments or chambers 25. The supply head which is also preferably 45 constructed of sheet metal, is further provided at an intermediate point with a valve chamber 26 which extends transversely of the head and is joined or connected to the opposed walls thereof. The wall of this 50 valve chamber forms the bottom walls of the upper chambers 25 of the supply head. The lower portion of the supply head is thus separated from the upper chambers 25, and 55 constitutes a common supply chamber 27 to which the gas is admitted from the service pipe. The walls of this lower chamber are provided with openings 28 to any one of which the service pipe may be conveniently 60 connected, the other openings being closed by means of suitable plugs. The supply head is held in connection with the end of the burner body by means of the hollow tapering tubes or pipes 29, the larger ends of 65 which are closed and provided with the threaded extensions 30. These extensions are adapted for threaded engagement in the respective plates 21 which close the ends of the burner flues or passages. It will be understood, from reference to Fig. 1 of the

drawings, that the supply head is arranged exteriorly of the stove or grate. The tubes or pipes 29 thus serve a double purpose, namely, to afford means for connecting the head to the burner body and also to support the burner body at one of its ends upon the wall of the stove. The stove wall is provided with openings through which these tapering tubes extend, the opposed walls of the chambers 25 of the supply head being 70 also formed with suitable openings for the reception of these connecting tubes. The smaller ends of the tubes 29 project outwardly through the outer wall of the supply head and are threaded to receive the cap 75 nuts 31, suitable packing washers 32 being arranged between said nuts and the wall of the supply head. Each of the plugs or tubes 29 is provided with an opening 33 through which gas may enter from the respective chambers of the supply head to the bores of said tubes. The outer smaller ends of the plugs 29 are also interiorly threaded to receive the valve stems 34, the inner ends of which are tapered or pointed for engagement with the valve seat 35 which surrounds an opening or passage formed through the closed end of the tubular plug and the extension 30 thereon. When the valve stem is engaged upon its seat, it will be obvious 90 that the supply of gas from the supply head to the flow or passage of the burner is completely cut off. Thus the flow or volume of gas entering the burner flues from the respective chambers of the head may be independently varied and increased or decreased, as may be found desirable. The cap nut 31 is also provided with a threaded opening for engagement by the threads of the valve stem, and within the cap nut between the 100 end wall thereof and the end of the tubular plug, suitable packing material is arranged. Thus, an absolutely secure connection of the head to the burner body is assured and a gas tight meeting between the same effected. 105

Within the valve chamber 26 of the burner head, above referred to, an elongated longitudinally tapering supply controlling valve cock 36 is rotatably mounted. The intermediate portion of this conical valve 36 is 110 of hollow formation, the solid end portions thereof being mounted in the opposed walls of the supply head. The smaller end of the valve is provided with a central threaded recess or socket to receive a clamping screw 115 indicated at 37. Between the head of this screw and the wall of the supply head, a suitable washer 38 is arranged. To the other or larger end of the valve, a handle or other suitable operating means 39 is connected. 120 The wall of the valve chamber 26 is provided in its lower portion with a central slot or opening 40 which is at all times in communication with a similar slot 41 formed in the valve 36 and communicating with the 125 130

hollow intermediate portion thereof. At either side of the slot 41 in the wall of the valve member, a slot 42 and an opening 43 are formed in the wall thereof. The slot 42 is adapted to register with a similar slot 44 in the upper portion of the wall of the valve chamber which opens into one of the upper chambers of the supply head while the opening 43 is adapted by a further turning movement of the valve member to register with an opening 45 in the wall of the valve chamber which affords communication between the interior of the hollow valve member and the other chamber of the supply head.

18 When these latter openings are in registration, the slot 42 is still in register with the slot 43 of the chamber wall so that gas is being simultaneously supplied to both chambers of the supply head. The gas is preferably supplied first to the outermost flue of the burner through the slot 42 in the valve member, in view of the fact that less time is required for the gas to fill said flue and issue from the tubes 19 than is consumed in filling 25 the rear flue of the burner, from which the gas finds its outlet through the jets 13. In this manner, it will be seen that we have provided means for separately controlling and regulating the supply of gas to the 30 burner flues.

In connection with a gas burner of the improved construction above described, we have devised a mixer whereby air may be mixed with the gas in order to obtain a blue flame, and quick and perfect combustion. 35 In the use of such a mixer, the burner is arranged within the stove or grate with the jet tips projecting upwardly, and in order to provide a support for the mixer, the base 40 wall 16 of the burner, is extended upwardly across the end of the burner body opposite to the supply head, to a slight distance above the body wall 12, as indicated at 46. This sheet metal wall 16 is then extended longitudinally of the burner in parallel relation to the wall 12, as shown at 47, and at the opposite end of the burner is extended downwardly as at 48, said latter portion being provided with spaced openings to receive 45 the tubular plugs 29. The extremity of this portion 48 of the sheet metal plate is then suitably secured to the end of the wall 16.

Our improved mixer is preferably constructed from a single sheet metal plate 50 which is bent into the cross-sectional form illustrated in Fig. 4. This plate, indicated at 49, has its longitudinal edge portions engaged upon each other. The intermediate portion of this plate is folded upon itself to produce a longitudinally extending rib 50. Between the opposed walls of this rib, the edges of the portions 49 of the plate are inserted. Metal clips indicated at 51 are bent around the ends of the portions 49 of the 55 sheet metal plate and riveted or otherwise

permanently secured thereto. The portions 52 of this sheet metal plate which constitute the opposed side walls of the mixer are bent into the form shown, the portions 49 of said plate which are arranged between these walls 70 being similarly bent. Thus, there is produced two separate and distinct longitudinally extending chambers, the upper portions 53 of which are quite narrow, while the lower portions thereof indicated at 54, gradually increase in width to the bottom of the mixer. The top walls of the portions 52 of these mixing chambers are perforated as shown at 55, and at this point, the mixture of air and gas issuing from said chambers 75 is ignited. The vertically extending end portion 46 of the mixer support is formed with an opening to receive a fastening bolt 56 whereby the burner and the support may be rigidly mounted and held upon one of the end walls of the stove body. The longitudinally extending portion 47 of the mixer support is formed with a central slot 57 which is designed to receive the rib 50 on the bottom of the mixer. It will be understood 80 that the ends of the mixing chambers are closed or plugged by means of suitable metal plates which are indicated at 58. It will also be obvious that if desired, instead of forming this mixer from a single sheet of 85 metal, the mixing chambers may be formed from individual metal sheets, the edge of one sheet being formed with the rib 50 to receive the other edge of said metal sheet and the edges of the metal sheet which constitutes the other mixing chamber. Upon each side of the longitudinally extending slot 57 in the horizontal supporting wall 47, a plurality of openings 59 are formed. Similar openings 60 in the bottom of the 90 mixer which communicate with the respective chambers thereof, coincide with the corresponding openings 59. In order to properly supply the gas from the chambers of the burner body to the respective mixing 95 chambers, the jet tips 13 and 20 are arranged in staggered relation. These two series of gas tips are arranged immediately beneath the respective series of openings in the supporting wall 47 upon which the mixer is mounted so that the gas is separately supplied in proper volume to each of the mixing chambers. As the gas enters the mixing chamber, it becomes mixed with the air also entering through the openings 60 in the bottom walls of said chambers so that when ignited at the top of the mixer, perfect combustion takes place and a blue flame is produced.

In Fig. 7 of the drawings, we have illustrated a slightly modified construction, wherein the mixer support instead of being formed as a continuation of the bottom wall 16 of the burner, is constructed from a separate and distinct sheet metal plate. This 125

plate includes the upper and lower parallel portions 61 and 62, respectively, which are connected by the vertical portions 63, one of said vertical portions being connected to 5 the opposite end of the sheet metal plate. The burner, indicated at 64, is mounted upon the lower horizontal portion 62 of the support, the edges of which are bent inwardly and crimped upon the turned-over 10 edges 17 of the base wall of the burner body. The upper longitudinal portion 61 of the mixer support is provided upon its longitudinal edges with the upstanding flanges 65, and also has a series of openings 66 formed 15 therein between said flanges. The mixer is constructed from two sheet metal plates, one of which is bent upon itself at intervals to form partition walls 67 of double thickness. The portions of the metal plate between 20 these walls, indicated at 68, constitute the front wall of individual gas receiving compartments. These latter walls extend above the partition walls and are bent inwardly or rearwardly over the several compartments, as clearly shown at 69. The other section of the mixer is also formed from a 25 single sheet metal plate which is bent at its ends to produce the outer wall 70 of the end compartments of the mixer. This metal plate is also bent upon itself at intervals to produce spaced vertical ribs 71, the portions 30 of the plate between said ribs constituting the rear walls 72 of the mixing chambers. The edges of the partitions 67 which are 35 formed in the other sheet metal plate above referred to, are engaged between the opposed walls of these ribs. From the lower edges of the chamber walls 72, the metal plate is extended laterally, and forwardly 40 as at 73, to form the bottom walls of the mixing chambers, and between these end walls, ribs 74 are formed in the plate in the same manner as the ribs 71. The forward edges of these bottom walls are bent over 45 and crimped upon the flanges 71' formed upon the lower edges of the front walls 68 of the several chambers or compartments of the mixer. At opposite ends of the mixer, outwardly projecting flanges 75 are formed 50 upon the bottom plate thereof and upon said flanges tongues 76 which are cut out of the vertical portions 63 of the mixer support and struck upwardly are adapted to be securely crimped or clamped whereby the 55 mixer is held against longitudinal shifting movement with relation to the support. In the bottom wall of each of the mixing chambers, an opening 77 is formed. It will be noted that the rearwardly projecting extensions 60 69 which are formed upon the upper ends of the front walls 68 of the mixing chambers are slightly spaced at their extremities above the flanges 78 which are formed upon the upper edges of the rear walls of the mixing chambers. Through

this space, the mixed gas and air issues. In the use of this type of mixer, the same is mounted upon the upper longitudinally extending portions 61 of the support, the ribs 74 spacing the bottom of the several mixing chambers from the support so that air may freely enter said chambers through the openings in the bottom walls thereof and the relatively large openings 66 which are provided in the horizontal portion 61 of the support. The jet tips communicating with the flues of the burner extend upwardly through these latter openings. The tips communicating with the respective flues are alternately arranged so that gas will be supplied from one flue to one chamber of the mixer while the next adjacent chamber is supplied from the other flue of the burner. 70 75 80

In Fig. 9, we have illustrated a slightly modified construction of the sheet metal mixer, wherein the section of the mixer in which the partition walls are formed is provided at one end of the opposed portions of the sheet metal plate constituting each of the walls with oppositely projecting clips or tongues 79, one of said clips extending beneath the contiguous edge of the top wall 69 of the adjacent mixing chamber while the other clip in the same chamber is disposed over and upon the upper surface of 85 90 95 said top wall. Thus, these top walls are also, at all times, maintained in fixed relation to the upper edges of the rear walls of the several mixing compartments or chambers. 100

In Fig. 10 of the drawings, we have disclosed still another type of mixer. In this construction, the mixer is formed from a single integral metal casting. This casting is of a general rectangular form, the same 105 being hollow and provided with a series of spaced partition walls 80 which divide the interior of the mixer into a plurality of gas and air receiving compartments. At the upper end of the mixer, the same is formed 110 with an inclined or obliquely disposed rib or flange through which outlets, indicated at 81, communicating with the several compartments are formed. Upon the base of 115 the mixer, the depending nipples 82 are 120 formed to receive the gas from the tips of the burner. It will be understood that the gas is alternately supplied from the respective flues of the burner to the mixing compartments of the mixer, in the manner hereinbefore described. 125

From the foregoing description, taken in connection with the accompanying drawings, the construction, manner of operation, and several advantages of the illustrated 125 embodiments of our invention will be fully and clearly understood.

It will be apparent, that the burner and mixer in either of the several forms above described may be constructed in circular 130

form by simply resorting to minor alterations in the construction of the several parts, as will be obvious. By arranging and mounting the mixer above the burner, the liability of back-fire into the mixing chamber is minimized and in case such back-fire should occur, it would be less liable to ignite the floor covering and result in a serious conflagration, owing to the comparatively great distance of the mixer from the floor. It is also manifest that as the mixer is constructed entirely of sheet metal, the same can be produced at very small manufacturing cost and will not add materially to the expense incident to the use of the burner.

It is to be understood that in the practical development of our invention, various alterations in the form, proportion, and arrangement of the several parts, will be found necessary, owing to the contingencies of the particular cases, and we therefore reserve the privilege of resorting to all such legitimate changes as may be fairly embodied within the spirit and scope of the invention as claimed.

Having thus fully described our invention, what we desire to claim and secure by Letters Patent is:—

1. A gas burner including a body having a gas receiving flue provided in one of its walls with a plurality of jet orifices, in combination with a gas supply head, a tapered tube connected to one end of the burner flue, means for detachably securing the supply head upon said tube, a supply controlling valve mounted in the head, and a valve mounted in said tube to regulate the supply of gas to the burner flue.

2. A gas burner including a body having non-communicating gas receiving flues each provided with a plurality of jet orifices, in combination with a gas supply head having individual gas receiving chambers for the respective flues of the burner, tubes detachably connected to one of the ends of the respective burner flues, means for removably securing the supply head upon said tubes, a valve mounted in said head to control the supply of gas to said chambers, and a needle valve mounted in each of said tubes to regulate the supply of gas to the respective burner flues.

3. A gas burner including a body consisting of a bottom wall and vertical channel-shaped end walls, gas receiving flues supported by said bottom wall between the end walls of the burner body, in combination with a supply head having individual supply chambers for the respective burner flues, tubes detachably mounted in one of the vertical end walls of the burner body and in the corresponding ends of the respective flues, means for removably securing the gas supply head upon said tubes, a valve mounted in said head to control the supply of gas

to said chambers, and a needle valve in each of said chambered tubes to regulate the supply of gas to the respective burner flues.

4. A gas burner including a body having a bottom wall, vertical end walls and a top wall, burner flues mounted upon the bottom wall between the end walls of said body and having jet orifices spaced from said top wall, said top wall having openings therein registering with the respective jet orifices, a mixer mounted upon the top wall of the burner body and having a plurality of mixing chambers to receive the gas from the respective burner flues, and gas supply means connected to one end of each of the burner flues.

5. The combination with a burner body provided with non-communicating flues and means for independently controlling the gas supply to said flues, of a mixer having a plurality of mixing chambers each provided with an inlet and an outlet, means constituting an integral part of the burner body for supporting the mixer in position above the same, and alternately arranged outlets communicating with the respective flues of the burner to supply gas to the individual chambers of the mixer.

6. The combination with a burner body provided with non-communicating flues and means for independently controlling the gas supply to said flues, of a mixer having a plurality of mixing chambers each provided with an inlet and an outlet, a support constituting an integral part of the burner structure extending above and in parallel relation to the flues, means for removably mounting the mixer upon said support, and alternately arranged outlets in communication with the flues of the burner to supply gas to the respective chambers of the mixer.

7. A gas burner including a body comprising channel body plates forming non-communicating flues and a sheet metal back plate constituting one side of the burner body and securing said channel plates together, said back plate being extended across the ends of said flues to close the same and having a portion disposed in parallel relation to the body to constitute a support, alternately arranged outlets communicating with the flues of the burner, in combination with a mixer provided with a plurality of mixing chambers removably mounted upon said support, each of said chambers having an inlet and an outlet, said inlets being arranged over the outlets of the burner flues to alternately receive the gas from the respective flues.

8. A gas burner including a sheet metal body plate, sheet metal burner flues secured upon said body plate, each of said flues being provided with a plurality of jet orifices, said body plate having a supporting portion extending in parallel relation to

the burner flues and spaced from the jet orifices, gas supply tubes removably mounted in the corresponding ends of the body plate and the burner flues, and a mixer secured upon the supporting portion of the body plate of the burner and provided with a plurality of mixing chambers to receive the gas from the respective burner flues, the bottom wall of each mixing chamber and the body plate of the burner having coinciding openings in alinement with the respective jet orifices of the burner.

9. A gas burner including a body having a sheet metal body plate provided with vertical channel-shaped end portions, burner flues mounted between the said end portions of the body plate and each having a plurality of jet orifices, said body plate having a portion connecting said end portions and disposed in spaced parallel relation to the

burner flues, said connecting portion of the body plate being formed with a central longitudinally extending channel and having openings therein on each side of the channel, gas supply means connected to one of the vertical ends of the body plate and the corresponding ends of the flues, in combination with the mixer having a central rib for removable engagement in the channel of the body plate, said mixer being provided with a plurality of mixing chambers each having an opening in its bottom wall to register with one of the openings in the body plate to receive the gas issuing from the respective jet orifices.
